UNITED STATES PATENT OFFICE.

GEORGE PEARS, OF TORONTO, CANADA.

DESIGN FOR A RANGE-GRADE.

SPECIFICATION forming part of Design No. 31,949, dated December 5, 1899.

Application filed November 6, 1899. Serial No. 736,057. Term of patent 7 years.

To all whom it may concern:

Be it known that I, GEORGE PEARS, a subject of Her Majesty the Queen of Great Britain, residing at Toronto, in the county of 5 York, Province of Ontario, Canada, have invented and produced a new and original Design for Range-Grates, of which the following is a specification, reference being had to the accompanying drawings, forming part thereof.

10 Figure 1 is a perspective view of a range-grate constructed in accordance with my design, the lower part being turned uppermost; and Fig. 2, a cross-section.

As shown in the drawings, the novel feature of the grate consists in a series of rings 15 supported by lugs. These lugs are in a line with one another, so as to give the appearance

of a bar or rib running the full length of the grate. The under side of each ring is cut away, so as to form an opening communicating with the hollow interior of the grate. Extending through the ends of the grate are the ends of an axle. 20

Having described my invention, what I claim as new, and desire to secure by Letters 25 Patent, is—

The design for a range-grate as herein shown and described.

Toronto, November 3, 1899.

GEORGE PEARS.
